STEAM HEATING SYSTEM

**Eric Alexander Murray, West Brunswick,
Victoria, Australia**

**Application February 8, 1933, Serial No. 655,703
In Australia February 10, 1932**

10 Claims. (Cl. 122—456)

This invention relates to heating systems in which steam from a boiler is passed through appliances used in various manufacturing, cooking and heating installations, and in which condensed steam (hereinafter called condensate) is collected and returned to the boiler.

10 The present invention relates particularly to an apparatus in which condensate gravitates to a lower sump from which it is transferred to an upper sump, and in which when a predetermined quantity of condensate is collected in the upper sump, steam from the boiler is admitted thereto until pressure in the boiler and the upper sump equalize allowing condensate to flow from the 15 sump to the boiler.

This invention includes improved valve devices to control the passage of steam from the boiler to the upper sump to equalize pressures and allow condensate to flow from the sump to the boiler; improved check valve devices to control outlet of steam from the upper sump after the upper sump is emptied; an improved relay valve to govern operation of the control valve; improved break valve devices which operate to reduce pressure in the upper sump when such pressure rises to such an extent that the functioning of the apparatus may be impaired; means for transfer of liquid from an open lower sump to the upper sump; a modified combined steam control and relay valve; and an improved check valve for use with said combined steam and relay valve.

In order that this invention may be more clearly understood it will now be described with reference to the accompanying drawings. It is to be understood that the illustrations are by way of example only and may be amplified or modified by those skilled in the art without departing from the spirit of the invention.

40 In the drawings:—

Fig. 1 is a diagram of improved apparatus having a closed lower sump.

Fig. 2 is a similar view of apparatus having an open lower sump.

45 Figs. 3 to 8 and Fig. 10 are on a larger scale.

Fig. 3 is a central longitudinal section of steam control and check valve mechanism in Fig. 1, showing the steam valves open and the check valves closed.

Fig. 4 is a similar view to Fig. 3 with the steam valves closed and the check valves open.

Fig. 5 is a central vertical section of break valve devices.

55 Fig. 6 is a central vertical section of the relay valve.

Fig. 7 is a central longitudinal section of part of the steam control check valves and auxiliary valve devices in Fig. 2.

60 Fig. 8 is a vertical section of combined steamer

control and relay valve mechanisms and modified check valve mechanism.

Fig. 9 is a diagram of modified apparatus.

Fig. 10 is a central section of the control and check valve devices in Fig. 9.

11 represents a boiler of any suitable type and size from which steam is conveyed through a pipe such as 12 to a heating system which may be according to the requirements of the user. From the heating system, steam and condensate is returned by a pipe 13 to a closed lower sump 14 (Fig. 1) or to an open lower sump 15 (Fig. 2) from which it is transferred through a pipe 16 having a non-return valve 17, to an upper sump 18. When high temperature condensate is being collected it is advantageous to distribute the condensate in sump 18 by means of a spray 19. A condensate return pipe 20 having a non-return valve 21 connects sump 18 to boiler 11.

Sump 18 is connected to the main steam supply by a pipe 22, the flow of steam being controlled by a pair of valves 23 which are partly balanced relatively to the steam pressure, one valve being slightly larger than the other so that they are normally influenced toward the open position but are readily movable to the closed position. Valves 23 are normally held closed by pressure on a diaphragm 24 in a casing 25. This diaphragm may be operated by any suitable medium such as steam, compressed air, or water, and in the arrangement illustrated the diaphragm is operated by steam which passes through a small pipe 26 connected to pipe 22. A control cock 27 on pipe 26 enables the pressure on diaphragm 24 to be accurately regulated.

Valves 23 are on a stem 28 which is adapted to be pressed by, but is separate from, a stem 29 on diaphragm 24. There is a strong spring 30 about stem 29. At the other side of valves 23 stem 28 has a head 31 which is pressed by a spring 32.

The diaphragm chamber 25 is connected by a pipe 33 to the casing 34 of partially balanced relay valves 35 which are so proportioned that they are normally closed by pressure of the medium which operates diaphragm 24, but are adapted to be readily opened by float operated means to provide an unrestricted passage to atmosphere through outlet 36 to relieve the pressure on the diaphragm 24. 45 50

To operate the relay valve 35, any suitable means may be used. As illustrated in Figs. 1, 2, and 9 sump 18 contains a float 37 the arm 38 of which is connected by known lost motion devices to one end of a stem 39 the other end of which enters the valve casing and terminates adjacent to valves 25.

A steam outlet pipe 40 from sump 18 is controlled by balanced check valves 41. A dia-

phragm 42 in casing 25 is adapted to press outwardly against the pressure of a spring 43 and its stem 44 is separate from but is adapted to press on the stem 45 of valves 41 and to normally hold them open against the pressure of a spring 46. The arrangement is such that when pressure on diaphragms 24 and 42 is released valves 23 open and valves 41 are closed.

When a closed lower sump is employed, pipe 40 is connected to a pressure reduction unit 47 from which a pipe 48, containing a non-return valve 49, extends to the factory return line 13. When an open lower sump 15 is employed, pipe 40 passes directly to said sump.

Break valve devices are provided which permit air and steam to escape from sump 18 through an outlet 50 when the difference between the pressures in the steam pipe 22 (and so in pipe 12) and sump 18 is reduced to such an extent that the efficiency of the apparatus may be impaired.

Outlet 50 contains a valve 51 from which a stem 52 extends to a diaphragm 53 in a casing 54. The space at one side of diaphragm 53 (herein called high pressure side) is connected to pipe 22 by a pipe 55 and the space at the other side of diaphragm 50 (herein called the low pressure side) is connected by a pipe 56 to pipe 40 on the outside of the check valves 41. At the low pressure side of diaphragm 53 is a spring 57 the pressure of which is adjustable by suitable means such as screw devices 58. When the pressure in the sump 18 (and so in pipe 40) rises above a predetermined limit, that pressure, assisted by spring 57, overcomes the steam pressure at the high pressure side of diaphragm 53 and opens valve 51.

When an open lower sump 15 is employed (Fig. 2) head 31 is formed to constitute a valve 59, whereby when valves 23 are closed, steam is allowed to by-pass through a pipe 60 to a steam ejector 61 in pipe 16, to lift condensate from sump 15 to sump 18 (Fig. 9).

When the main steam and relay valves are combined (Fig. 8) the valves 23 are carried by a tubular stem 62 connected to a diaphragm 63. Extending through stem 62 is a pipe 64 the inner end of which is adapted to be closed by a relay valve 65 on a slide stem 66. Valve 65 is controlled by means of an angular extension 67 on float arm 38. The space at one side of the diaphragm 63 is open to main steam pressure through a passage 68 and a pipe 69 having a control cock 70. The space at the other side of diaphragm 63 is connected by a passage 71 to a chamber 72 at the outlet side of valves 23. A check valve 73 is controlled by a diaphragm 74. This diaphragm is operated to open the valve by steam pressure through a connection 75 to pipe 69, and is influenced toward closed position by a spring 76.

In the arrangement shown in Figs. 9 and 10 the valves 23 are controlled by a diaphragm 24 and a spring 32 as before described, but valve 59 functions as a check valve so that when valves 23 are closed, steam passes from the sump 18 through a pipe 77 to the factory line 13, non-return valves 78 and 79 being provided to prevent back pressure.

In operation, referring particularly to Fig. 1 and Figs. 3 to 6, condensate flows from the factory line 13 to sump 15 and is forced through pipe 16 to upper sump 18. When condensate rises to a predetermined level in sump 18 float 37, by means of its arm 38, operates stem 39

to open relay valves 35 allowing steam from diaphragm casing 25 to escape to atmosphere and reduces the pressure on diaphragms 24 and 42. As soon as the pressure between these diaphragms falls sufficiently springs 30 and 43 press the diaphragms toward each other, releasing the pressure on the valve stems 29 and 45, allowing valves 23 to be opened by spring 32 and valves 41 to be closed by spring 46. Steam will then flow from pipe 22 to sump 18 until the pressure in the sump equals the pressure in boiler 11. As soon as these pressures equalize, condensate will flow by gravity from sump 18 through pipe 20 past non-return valve 21 to boiler 11. As the level of the condensate in sump 18 falls, ball 37 also falls, but by reason of the lost motion devices the ball arm 36 has freedom of movement until the sump is empty or until condensate therein falls to a predetermined level, at which time motion is imparted to stem 39 to close the valves 35. As soon as valves 35 close, pressure is again exerted on diaphragms 24 and 42, closing valves 23 and opening valves 41. The opening of valves 41 allows steam to escape from the sump 18 through pipe 40 and pressure reduction unit 47 thence back to factory return line 13. When pressure in sump 18 drops sufficiently the apparatus will again function to feed condensate to the sump.

If, when valves 41 open, the pressure in the sump 18 and so in pipe 40 rises sufficiently to render the apparatus inefficient, causing condensate to bank up in the factory return line 13, then such pressure aided by the pressure of springs 57 will overcome the pressure of steam on diaphragm 53 and open valve 51, allowing air and steam to escape from sump 18 to atmosphere and causing the pressure in the sump to drop. As soon as the pressure in sump 18 falls sufficiently steam pressure again operates diaphragm 53 to close valve 51 and the apparatus resumes its normal functioning.

Referring to Fig. 2 as the lower sump 15 is open to atmosphere the pressure in sump 18 cannot rise sufficiently to impair the efficiency of the apparatus and the break valve devices 51 to 58 and pressure reduction unit 47 are not necessary.

In this case the apparatus functions as before described but when valves 23 are closed, valve 59 is open and steam by-passes from pipe 22 to pipe 60 operating ejector 61 to lift condensate from sump 15 through pipe 16 to the sump 18.

In the arrangement shown in Figs. 9 and 10 condensate flows directly to sump 18. Valves 23 and 35 function as before described but when valves 23 are closed and valve 59 is open, steam may pass from the sump through pipe 77 past non-return valve 78 back to factory return line 13. When valves 23 open, valve 59 closes, and steam is admitted to sump 18 until pressures equalize as before described, non-return valve 79 preventing the passage of steam to the pipe 13.

Part of the relatively small quantity of steam in the sump passes along pipe 77 when the sump valve 23 closes. This steam is distributed in the factory lines 13 and slightly raises the temperature of the condensate but the quantity of steam is so small relatively to the pipe system that normal functioning is not interrupted.

In the construction shown in Fig. 8, when relay valve 65 is closed, steam from pipe 22 operates diaphragms 63 and 74, closing valves 23

and opening valve 73. As soon as valve 65 is opened by the connections to the float arm, steam escapes through tube 64 to atmosphere relieving the pressure on diaphragms 63 and 74, allowing valves 23 to be partially opened by steam pressure and valve 73 to close. As steam passes through valves 23 some of it finds its way through chamber 72 and passage 71 to the other side of diaphragm 63 and operates it to move valves 23 to the fully open position. When the float falls, arm 38 and extension 67 operate to close relay valve 65 after which valve 73 is opened by steam pressure and pressure on diaphragm 63 closes valves 23.

15 What I claim is:

1. In steam heating systems, a boiler, means to convey steam through a heating system, a sump, means to convey condensate from said system to said sump, a steam connection between the boiler and the sump, a pipe connecting the sump and the boiler, control valve means in the said steam connection, a diaphragm arranged to be operated by fluid pressure to close the control valve, means to release said fluid pressure when the liquid in the sump rises to a predetermined level, and spring means arranged to open said valve when the pressure on the diaphragm is released.

2. In steam heating systems as in claim 1 an outlet from the sump, a valve to control said outlet and a diaphragm adapted to be operated simultaneously with the diaphragm of the control valve devices, to open said valve when the control valve is closed, the said outlet being connected to a pressure reduction unit which is in turn connected to a closed sump.

3. In steam heating systems a boiler, a sump, means to convey condensate to said sump, a condensate return connection between the sump and the boiler, a steam supply connection between the boiler and the sump, a control valve in said supply connection, and a relay valve to govern the operation of said control valve, the said relay valve being partially balanced relatively to pressure and being pressed toward closed position by such pressure.

4. In steam heating systems a boiler, an upper sump, means to convey condensate to said sump, a condensate return connection between the sump and the boiler, a steam supply connection between the boiler and the sump, a control valve in said steam supply connection, an open lower sump, a connection from said lower sump to said upper sump, an ejector in the last mentioned connection and valve means whereby, when the control valve is closed, steam is directed to the ejector to cause condensate to be fed to the upper sump.

5. In steam heating systems, a sump, means to convey condensate from the sump to a boiler, and a break valve arranged to be operated when the pressure in the sump rises above a predetermined limit to allow steam and air to escape from the sump until the pressure falls below said limit, a diaphragm to control the break valve, said diaphragm being connected at one side to a steam supply and at the other side being pressed by a spring, the spring pressed side being also connected to the said sump when the latter is not connected to the steam supply.

6. In steam heating systems a condensate receiving sump, a boiler to which condensate passes from the sump when pressures in the sump and the boiler are equalized, means to control admission of steam to the sump, said means

including a pair of partially balanced valves normally influenced toward open position and mounted on a slideable hollow spindle one end of which is connected to a diaphragm, a fixed hollow member passing through said spindle and terminating in a space at one side of the diaphragm, a relay valve adapted to co-operate with a seating on the end of the fixed hollow member, means to control said relay valve, means whereby when the relay valve is closed steam is admitted to one side of said diaphragm to cause the control valves to close and further means whereby when the relay valve is opened steam is admitted to the other side of said diaphragm to cause the control valves to open.

7. In steam heating systems, a boiler, means to convey steam through a heating system, a sump, means to convey condensate from said system to said sump, a steam connection between the boiler and the sump, a pipe connecting the sump and the boiler, control valve means in the steam connection, said means comprising a pair of valves one of which is larger than the other, the said valves being so arranged that they are influenced by steam pressure toward the open position, a diaphragm arranged to be operated by fluid pressure to close the control valve, means to release said fluid pressure when the liquid in the sump rises to a predetermined level, and spring means arranged to open said valve when the pressure on the diaphragm is released.

8. In steam heating systems, a boiler, means to convey steam through a heating system, a sump, means to convey condensate from said system to said sump, a steam connection between the boiler and the sump, a pipe connecting the sump and the boiler, control valve means in the steam connection, a diaphragm adapted to be operated by fluid pressure to close the control valve, means to release said pressure when the liquid in the sump rises to a predetermined level, a stem extending from the control valve, a stem extending from the diaphragm toward the control valve stem, a spring which when pressure on the diaphragm is released presses the diaphragm stem away from the control valve stem, and a spring to open the control valve when its stem is freed.

9. In steam heating systems, a boiler, a sump, means to convey condensate from the sump to the boiler, a break valve adapted to be operated when the pressure in the sump rises above a predetermined limit to allow steam and air to escape from the sump until the pressure falls below said limit, a diaphragm to control the break valve, said diaphragm being connected at one side to a steam supply and at the other side being pressed by a spring, the spring pressed side being also connected to the said sump when the latter is not connected to steam supply.

10. In steam heating systems as in claim 6, a steam outlet from the sump, a valve to control said outlet, spring means arranged to actuate said valve toward closed position, a diaphragm connected to said valve, a chamber containing said diaphragm, a connection from said chamber to a fluid supply, the arrangement being such that when the relay valve is closed fluid pressure actuates said diaphragm to open the steam outlet valve, and when the relay valve opens the fluid pressure is released and said spring closes said steam outlet valve.
